UNITED STATES PATENT OFFICE.

THOMAS B. LASHAR, OF BRIDGEPORT, CONNECTICUT, ASSIGNOR TO ASSOCIATED SILVER COMPANY, OF CHICAGO, ILLINOIS, A CORPORATION OF ILLINOIS.

DESIGN FOR A SPOON OR SIMILAR ARTICLE.

54,854.

Specification for Design.

Patented Apr. 13, 1920.

Application filed March 20, 1919. Serial No. 283,941. Term of patent 7 years.

To all whom it may concern:

Be it known that I, THOMAS B. LASHAR, a citizen of the United States, residing at Bridgeport, county of Fairfield, State of Connecticut, have invented a new, original, and ornamental Design for a Spoon or Similar Article, of which the following is a specification, reference being had to the accompanying drawing forming a part thereof.

In the drawing Figure 1 is a front elevation illustrating a spoon embodying my novel design;

Fig. 2 is a section, on an enlarged scale, on the line 2—2 in Fig. 1, and

Fig. 3 is a section, on an enlarged scale, on the line 3—3 in Fig. 1.

What I claim is:—

The ornamental design for a spoon or similar article, as shown.

In testimony whereof I affix my signature.

THOMAS B. LASHAR.
